PACKAGE

William J. Elvin, Frostburg, and William T. Stearn, Cumberland, Md., assignors to Celanese Corporation of America, a corporation of Delaware

Application July 3, 1940, Serial No. 343,698

8 Claims. (Cl. 242—18)

This invention relates to a novel means for winding and twisting yarn, and relates more particularly to a means for forming large size packages of yarn.

The formation of large-sized packages of yarn, and more particularly the formation of such packages on single-end bobbins, has presented numerous difficulties. In forming such packages the yarn must be wound under sufficient tension to form a package which is not only firm but which will retain its form when handled. Where there is insufficient or uneven tension in the yarns the resulting package will be soft and tend to come apart at the end, or else subsequent twisting operations will give a yarn lacking in uniformity. Furthermore, the tension under which the winding takes place must be such that the turns of each layer are wound closely and firmly without any tendency to slip and jam between the threads of the layer beneath. Threads which jam in this manner tend to break in subsequent unwinding operations which causes delay and considerable wastage of thread. It is, therefore, desirable that a winding device be obtained to overcome these difficulties.

An object of our invention is to provide a take-up device for winding and twisting yarn into large firm packages from which the yarn may be easily un wound for further processing.

Another object of our invention is to provide a means for horizontally winding large yarn packages in which the tension variations in the yarn are reduced to a minimum and the resulting yarn is wound with substantially uniform tension.

Still another object of our invention is to provide a means whereby full yarn packages may be easily and quickly replaced by empty yarn supports or packages.

Other objects of our invention will appear hereinafter from the following detailed description.

The formation of large packages of yarn is very desirable in many textile operations. Such packages may be used as supply packages for the formation of other large yarn packages in which the yarn characteristics, such as twist, may be varied and are also desirable for the reason that large yarn packages decrease the number of knots necessary when the yarn is later used in warping or in weaving. In addition, the larger yarn packages require less frequent changing on winding, twisting and warping apparatus and fewer spools are necessary for shipping a definite weight of yarn.

In order further to illustrate our invention, ref-

erence may be had to the accompanying drawings, in which

Fig. 1 is a side view of one embodiment of our invention showing the path of the yarn,

5 Fig. 2 is a front elevation of this embodiment showing the spool spindle guide partly in section,

Fig. 3 is a vertical view of this embodiment,

Fig. 4 is a side view of another embodiment of 10 our invention,

Fig. 5 is a front elevation of this latter embodiment, and

Fig. 6 is a vertical view of the embodiment of 15 our invention shown in Figs. 4 and 5.

Like reference numerals represent like elements throughout the several views of the drawings.

Referring now to the drawings, and particularly to Fig. 2, there is shown a spool 7 through which runs a spindle 8, the ends of which protrude beyond the spool and which are positioned 20 in the spindle guides 9. The spool 7 rests upon and is driven by a cork roller 10 which acts as a friction drive, the roller 10 being in turn driven by shaft 11 which is operated by any suitable means, and which serves to drive a plurality of rollers 10. In Fig. 1 the yarn 12 which is being 25 twisted and wound on to the take-up package or spool 7 is led upward from a rotating twisting take-off bobbin 13 through a pigtail guide 14 and 30 over guide bar 15. The yarn 12 is then led through a traverse guide 16 which is attached to a reciprocating traverse bar 17, the reciprocation of which deposits the yarn evenly on the spool 7.

35 The package is formed by setting an empty spool 7 in position as shown in Fig. 2 and permitting it to come in contact with and be driven by the rapidly rotating friction drive cork roller 10. The yarn is passed through the traverse 40 guide 16 and is laid on the spool 7. As the spool 7 takes up the yarn the traverse bar 17 reciprocates and the traverse guide 16 guides the yarn evenly on the spool. As the spool 7 becomes 45 filled with yarn, it rises higher and higher on the driving cork roller 10 and the ends of the spindle 8 move in the spindle guides 9 to form or shape the yarn on the spool 7. When the spool is full it rises to the position A as shown by broken lines in Figs. 1, 2 and 3, and the spindle ends rise to 50 the position 8'. The spindle guides 9 are supported as by brackets 18. The full spool of yarn may be removed by merely lifting it out of the yarn guides 9 and an empty spool may be dropped in place to wind the next package.

In accordance with another embodiment of

our invention as illustrated in more detail in Figs. 4, 5 and 6, the empty spool 7 upon which the yarn is to be wound is supported on a spindle 8, the ends of which pass through arms 19 provided with holes 20 for receiving the ends of the spindle 8 and permitting rotation therein without loose movement. The arms 19 are pivotally mounted on a bar 21 by means of holes 22 and move freely about the bar 21. On the left-hand arm 19 is attached a spring 23 as by rivets 24, the lower end of which spring bears against the end of the spindle 8 and maintains a light pressure thereon. Horizontal movement of the empty spool from the left to the right due to the light pressure of the spring 23 is prevented by contact of the bevelled base with the friction drive cork roller 10 mounted on shaft 11 against which the spring 23 forces the base of the spool.

The package is formed by leading a yarn 12 on to the spool 7. The yarn 12 is led upward from a rotating twisting take-off bobbin 13, through a pigtail guide 14 and over a guide bar 15. The yarn 12 is then led through a traverse guide 16 which is attached to a traverse bar 17, the reciprocation of which deposits the yarn evenly on the spool 7.

The spool 7 is driven or rotated by the cork friction drive roller 10 upon which it rests as shown in Fig. 4. The roller 10 is turned by the shaft 11 which passes through it, which in turn is driven by any suitable means which serves to drive a plurality of rollers 10. When the yarn 12 is thrown on to the rotating spool 7 it proceeds to wind on the spool and it is evenly distributed along the length of the spool by the traversing guide 16 attached to the moving traverse bar 17. As the spool 7 becomes filled with yarn it rides in an increasingly higher position on the cork friction drive roller 10 since the arms 19 holding the spool 7 are free to pivot about the bar 21. As the spool 7 rides higher on the cork roller 10 the base of the spool is held constantly in contact with the base of the cork roller 10. Since the traverse distance is constant, the spool being filled with yarn moves gradually to the right as it fills due to the spring pressure and the yarn is wound on the spool to form a yarn package of a particular controlled shape. When full, the package is in the raised position B and has the shape as shown by the broken lines in Figs. 4, 5 and 6. The full package may be removed by merely slipping the spindle 8 from the holes 20 in the arms 19 and it may be replaced in a similar manner by slipping the spindle of an empty spool in the holes.

Winding yarn packages by means of this device gives a package of very low tension differential which is ideally suited for many textile uses as hereinbefore stated. Spindle speeds of as high as 11,500 R. P. M. and higher may be easily employed using this surface drive method.

It is to be understood that the foregoing detailed description is merely given by way of illustration and that many variations may be made therein without departing from the spirit of our invention.

Having described our invention, what we desire to secure by Letters Patent is:

1. A yarn package winding device comprising driving means adapted to drive a yarn package by frictional engagement with yarn on the surface thereof, traversing means adapted to traverse yarn to and fro over part of the length of said package, and means for producing a relative motion in the direction of the axis of said pack-

age between said package and the field of traverse of said traversing means as the axis of said package moves away from said driving means during the building up of said package, so as to shape said package during winding.

2. A yarn package winding device for winding yarn on a package support having a conical base, said device comprising driving means adapted to drive a package by frictional engagement with yarn on the surface thereof, traversing means having a traverse covering part of the length of said package, and means for producing a relative motion in the direction of the axis of said package between said package and said traverse as the axis of said package moves away from said driving means during the building of said package, in such a way that one end of said traverse always reaches the conical base of the package support while the other end shapes the apex of said package.

3. A yarn package winding device for winding yarn on a package support having a conical base, said device comprising a spindle for the package support, said spindle being free to move laterally as the package builds up, driving means adapted to drive a package by frictional engagement with yarn on the surface thereof, traversing means having a traverse covering part of the length of said package, and means for urging said spindle longitudinally so as to maintain the conical surface of the package support in contact with the edge of the driving means, so as to produce a relative motion in the direction of the axis of said package between said package and said traverse as the axis of said package moves away from said driving means during the building of said package, in such a way that one end of said traverse always reaches the conical base of the package support while the other end shapes the apex of said package.

4. A yarn package winding device for winding yarn on a package support having a conical base, said device comprising a spindle for the package support, driving means adapted to drive a package by frictional engagement with yarn on the surface thereof, traversing means having a traverse covering part of the length of said package, and slotted guides adapted to accommodate the ends of said spindle and inclined to said spindle at an angle substantially equal to the semi-vertical angle of the conical base of said package support, so as to produce a relative motion in the direction of the axis of said package between said package and said traverse as the axis of said package moves away from said driving means during the building of said package, in such a way that one end of said traverse always reaches the conical base of the package support while the other end shapes the apex of said package.

5. A yarn package winding device for winding yarn on a package support having a conical base, said device comprising a spindle for the package support, a pair of pivoted arms having loose bearings for the ends of said spindle, driving loose bearings for the ends of said spindle, driving means adapted to drive a package by frictional engagement with yarn on the surface thereof, traversing means having a traverse covering part of the length of said package, and spring means on one of said arms, acting on the end of said spindle to urge it longitudinally so as to produce a relative motion in the direction of the axis of said package between said package and said traverse as the axis of said package

moves away from said driving means during the building of said package, in such a way that one end of said traverse always reaches the conical base of the package support while the other end shapes the apex of said package.

6. A yarn package winding device comprising a horizontal frictionally driven take-up package turning on a spindle, a horizontal friction drive bearing on and supporting said take-up package and having a stationary axis of rotation, a yarn supply, a traverse rod with a yarn traverse guide attached thereto for guiding the yarn on to said take-up package, and slotted spindle guides inclined with respect to said stationary axis of rotation for controllably changing the position of the axis of rotation of the take-up package to shape the yarn package as it forms.

7. A yarn package winding device comprising a horizontal frictionally driven take-up package turning on a spindle, a horizontal friction drive bearing on and supporting said take-up package and having a stationary axis of rotation, a yarn supply, a traverse rod with a yarn traverse guide attached thereto for guiding the yarn on to said

take-up package, pivotally mounted take-up package spindle receiving arms and a spring tensioned member bearing axially on said take-up package spindle for gradually changing the position of the axis of rotation of the take-up package to shape the yarn package as it forms.

8. A yarn package winding device comprising a horizontal frictionally driven single base take-up package turning on a spindle, a horizontal friction drive bearing on and supporting said take-up package and having a stationary axis of rotation, a yarn supply, a traverse rod with a yarn traverse guide attached thereto for guiding the yarn on to said take-up package, pivotally mounted take-up package spindle receiving arms and a spring tensioned member bearing axially on the end of said take-up package spindle adjacent to the package base for gradually changing the position of the axis of rotation of the take-up package to shape the yarn package as it forms.
